ATTORNEY.

UNITED STATES PATENT OFFICE.

SOLOMON SCHWARZSCHILD, OF ROCHESTER, NEW YORK, ASSIGNOR TO
JENNIE SCHWARZSCHILD, OF SAME PLACE.

HEATING APPARATUS.

SPECIFICATION forming part of Letters Patent No. 670,437, dated March 26, 1901.

Application filed June 26, 1900. Serial No. 21,665. (No model.)

To all whom it may concern:

Be it known that I, SOLOMON SCHWARZSCHILD, a citizen of the United States, residing at Rochester, New York, have invented 5 certain Improvements in Heating Apparatus, of which the following is a specification, reference being had to the accompanying drawings.

My invention relates to certain improvements in heating apparatus, designed more particularly for use in connection with stoves heated by gas, but applicable also to oil or gasolene stoves.

My improvements are fully described and 15 illustrated in the following specification and the accompanying drawings, the novel features thereof being specified in the claims annexed to the said specification.

In the accompanying drawings, representing 20 my improvements in heating apparatus, Figure 1 is a perspective view. Fig. 2 is a section on the line 2 2, Fig. 1. Fig. 3 is a partial plan view. Fig. 4 represents the escape-opening.

25 A represents the body or casing of any suitable gas, oil, or gasolene stove to which it is desired to apply my improvements. The stove may be provided with a plurality of burners of any ordinary or preferred construction. The upper plate B of the stove A is provided with one or more orifices C, the 30 number and location of such orifices depending upon the number of burners employed.

D is a perforated cover placed above the 35 upper plate B and provided with flanges E all around, whereby a recess or heating-chamber F, Fig. 2, is formed below the top and between it and the perforated upper plate B of the stove. The top is provided with a plurality of lid-openings G, corresponding in 40 number and arrangement with the openings C in the upper plate B.

H represents removable lids adapted to 45 close the openings G. The lids H are perforated, preferably near one edge, as indicated at I, these perforations being also adapted for lifting the lids by means of the ordinary stove-lifter. The cover is provided with escape-orifices J of any suitable shape and 50 adapted to be closed by the register or other valves K. In the construction shown these

valves K are recessed into the upper side of the top, so that its whole upper surface is flat. For the admission of air into the inside of the casing A suitable perforations L may 55 be employed.

In the practical use of my improvements the burner or burners may be lighted within the casing, and the desired culinary operations may be performed on the cover with or without 60 the removal of one or more of the lids H. The heating-chamber formed above the stove by the recess in the lower side of the cover D secures perfect combustion and a material economy in fuel. Where a number of escape- 65 openings are employed, those nearest the ignition burner or burners may be closed by the valves K, while those at a distance may be opened, so as to secure passage of the heat laterally through the heating-chamber, where- 70 by a single burner may be employed to effectively heat the whole cover.

The location of the orifice I in the lid H near one edge permits the escape of the heated gases at one side of a culinary vessel resting on the cover. The cover being open at the bottom, with the edges of the flanges thereof resting on the upper plate of the stove, the lateral circulation of the heated gases is promoted by their escape through the lid- 75 openings in the cover, which occurs whether the other openings are open or closed; but the best results are secured by the use of one or more of the registers, by which the heat is strongly deflected to parts of the cover at one 80 side of the burner.

My improvement is cheap and durable, being readily made of iron and of such shape and dimensions that it may be applied to any of the different styles of stoves now in use. 90 It may be ornamented or finished, as by nickeling, in any suitable or preferred manner.

I claim—

1. The combination of a stove having a plurality of burners with a removable cover provided with a plurality of lid-openings and means for directing the products of combustion from any of said burners through or by any of said lid-openings, substantially as described. 95

2. The combination of a stove having a plurality of burners with a removable cover there-

for having two or more lid-openings, each provided with a lid or cover, and a suitable damped outlet-opening, said openings being so located that the products of combustion from 5 any one or more of said burners may be directed to any one of said openings, substantially as described.

3. The combination of a gas-stove having a plurality of burners with a removable cover 10 therefor, said cover being open on its lower side and provided with a series of lid-open-

ings having lids for closing them and with a plurality of damped outlet-openings, whereby by the products of combustion from a single source of heat may be directed to different 15 portions of the removable cover, substantially as described.

SOLOMON SCHWARZSCHILD.
